UNITED STATES PATENT OFFICE.

OLIVER G. SANDAGE, OF NEW YORK, N. Y., ASSIGNOR OF TWO-THIRDS TO DOEHLER
DIE CASTING COMPANY, A CORPORATION OF NEW YORK.

ART OR METHOD OF AND APPARATUS FOR CASTING FLUID METALS.

1,156,557.

Specification of Letters Patent. Patented Oct. 12, 1915.

Application filed August 1, 1913. Serial No. 782,393.

To all whom it may concern:

Be it known that I, OLIVER G. SANDAGE, a citizen of the United States, residing at the borough of Brooklyn, in the city of New York, county of Kings, and State of New York, have invented certain new and useful Improvements in the Art or Method of and Apparatus for Casting Fluid Metals, of which the following is a specification, reference being had therein to the accompanying drawings, which form a part thereof.

My invention relates to improvements in the art or method of, and apparatus for, casting fluid metals, and more particularly to an art or method and apparatus for use in connection with steel dies utilizing air or other gases under pressure for forcing the metal into the mold.

The main object of the invention is to provide a method of casting fluid metals utilizing a bottom pour melting pot, whereby that portion of the metal delivered to the die is maintained at the proper temperature to insure a ready flow of the metal to all parts of the die while excluding dross, oxides or other impurities from the metal delivered to the die.

A still further object is to provide such a method whereby excessive splashing of the metal in the pot with the introduction of the gaseous charge under pressure will be avoided, and the oxidation of the metal from said gas reduced to a minimum.

A still further object is to provide a method of this character wherein the gas under pressure will be applied to the metal and the metal delivered to the mold or die thereunder in a manner to insure the delivery of the molten metal substantially instantaneously and in such volume as will completely fill the entire mold or die.

A still further object is to provide an apparatus by means of which my aforesaid method or art may be conveniently practised without likelihood of the escape of the metal while passing from the melting pot to the mold or die.

A still further object is to provide an apparatus wherein the mold or die may be rapidly brought into the operative relation to the melting pot, and secured relative thereto in a manner to insure a sufficiently

tight fit to prevent the escape of the metal between the gate of the die and the outlet of the melting pot. 55

A still further object is to provide an apparatus of this character wherein the pressure within the melting pot and the delivery of the metal to the die may be controlled in a manner to insure the timely delivery of the molten metal to the die under the proper conditions. 60

A still further object is to provide an apparatus so constructed as to permit the rapid charging of the die and the ejection of the casting to insure high capacity of the machine. 65

A still further object is to provide an apparatus which may be adjusted to adapt it to dies of different sizes or to insure the proper fitting of a die with relation to the melting pot. 70

A still further object is to provide in connection with an apparatus of this character, a sprue former, by means of which the metal may be delivered from the melting pot to the die, said sprue former being capable of removal from the die to prevent freezing of the ingate of the die. 75

A still further object is to provide an apparatus of this character wherein the operator will be protected from possible injury due to the escape of molten metal between the die and the melting pot. 80

A still further object is to provide an apparatus of this character wherein the various operations may be conveniently controlled or practised by the operator. 85

A still further object is to provide an apparatus wherein no sprue cutter is required, the gate controlling the outlet of the melting pot acting to separate the metal entering the die from that in the melting pot. And a still further object is to provide an apparatus wherein the gate controlling the outlet of the melting pot will be automatically closed and normally maintained closed to prevent the escape of the metal from the pot excepting when the die is in the operative relation thereto. 90

The invention consists primarily in a method or art of casting fluid metals embodying therein the subjection of a confined mass of molten metal contained in a 95

bottom pour melting pot to gas under pressure thereafter permitting a small portion of the molten metal to flow under said pressure through the outlet of said pot into a 5 mold and thereafter simultaneously closing said port and forcing the metal therein outwardly of said melting pot; and in such novel steps as are hereinafter set forth and described; and in the novel features of construction and combination of parts in the apparatus hereinafter set forth and described, all as more particularly pointed out in the claims hereto appended.

Referring to the drawings:—Figure 1 is 15 a perspective view of an apparatus embodying my invention and adapted for use in practising my improved art or method; Fig. 2 is a vertical section thereof on a smaller scale, showing the mold in position to have 20 the molten metal charged thereto, the guard being indicated by dotted lines in the lowered position; Fig. 3 is a detail view in section of the removable sprue former removed from a mold, the sprue being 25 shown in connection with a portion of the mold; and Fig. 4 is a detail front view of the means for forcing the mold toward the melting pot, a conventional mold, and a portion of the melting pot also being shown.

30 Like letters refer to like parts throughout the several views.

Heretofore in the art of casting fluid metals under fluid pressure, it has been the practice to subject the metal in a charging 35 pot drawing its supply of metal from a melting pot, to the action of air under pressure in a manner to force a portion of the fluid metal contents upwardly into the mold, a sprue cutter being used to prevent 40 back flow of the metal to the die. Where the metal has been forced directly from the melting pot into the mold, this has been the usual, and so far as I am aware, the only method ever suggested or attempted.

45 Contradistinguished from this method is a method by which a metal is fused in a crucible apart from the mechanism for charging the mold, and delivered in limited quantities to a bottom pour pressure chamber from whence the entire charge of metal 50 is forced under air pressure into the mold. In actual practice, the first method above referred to has been found impracticable because of the rapid deterioration of the metal in the charging pot or pressure chamber; the difficulty of keeping the metal in the charging pot or chamber at the right temperature, and a marked tendency of the 55 metal to back flow forming invisible blow holes in the castings produced. The castings also frequently contained flaws resulting from the presence of oxids in the charging pot or chamber.

60 While the second method above referred to possessed none of the disadvantages

above enumerated, and was especially suited for use in making casting of the higher fusing metals, the operation of a machine capable of use in practising that method was too slow for use in connection with 70 metals and alloys having a low fusing point.

To obviate the difficulties enumerated above, I employ a method or art in which the metal for charging is forced directly 75 from a bottom pour melting pot into the mold by means of air or other fluid pressure, thus securing the advantages of an avoidance of contact of any portion of the metal to be charged into a mold with the air or other gas under pressure; an ability to maintain any portion of the metal in the melting pot to be charged into a mold at the desired temperature up to the time it is to be so charged; the automatic separation 80 of the oxids and other dross from the metal adjacent the outlet port and its accumulation near the top of the melting pot where it will in a measure protect the contents of the melting pot from the air or other gases; and the instantaneous delivery of sufficient metal to fill the mold without possibility of back flow, the quantity of metal delivered 85 being coincident with the capacity of the mold. As a further incident I have found little or no tendency of the metal to splash, which I attribute in part to a possible sluggishness of the metal toward the top of the melting pot due to lower temperatures at 90 this point.

95 In the practice of my invention, I fuse a mass of metal such as aluminum, or the white metal alloys, contained in a bottom pour melting pot, by impinging a melting flame upon the pot adjacent the outlet port. This brings the metal toward the bottom of the pot to the desired molten state when it will readily flow, the metal in the upper portion of the pot being more sluggish because further removed from the heating 100 flame. The outlet port is normally closed so that the entire mass of metal is confined within said pot except when this port is opened. The melting pot being closed at the top, air or other fluid pressure may be 105 readily introduced thereto for delivering a charge into the mold. To insure practically an instantaneous delivery of the entire charge into the mold and thus avoid any portion thereof entering the mold under gravity and setting by chilling before the mold is filled, I admit the air or other gas under pressure to the melting pot before opening the outlet port, or while the entire 110 mass is thus confined. To relieve this pot from unnecessary stress, I bring the ingate of the mold into position relative to the melting pot outlet port, before subjecting the mass to air or other gas pressure, and when the required pressure is developed in 115 120 125 130

the melting pot, immediately open said outlet port.

The opening of the outlet port will permit the air or other gases to instantly expand, 5 forcing a small portion of the mass of molten metal in a substantially solid stream and without spraying into, and compacting it within, the mold. The outlet port is then immediately closed, and the pressure within 10 the melting pot relieved by venting. It will be observed that the metal delivered from the melting pot is drawn from the heat zone of highest temperature, and that this metal does not come in contact with any portion 15 of the air or gas used for forcing it from the pot.

Castings made by my method or art have a smooth finish and sharp outlines, and are free from dross, oxids, blow holes or other 20 apparent or concealed defects.

The closing of the outlet port separates the metal of the casting from that in the pot, the valve acting as a sprue cutter. The high 25 temperatures about the outlet port permit the free actuation of the valve either in opening or closing.

Fresh ingots of metal are introduced into the melting pot from time to time to maintain a sufficient mass of molten metal therein.

30 The essentials of my method or art are the fusing and maintenance of a mass of metal in a bottom pour melting pot; the closing of the outlet port of said pot so as to normally confine the mass of metal within 35 said melting pot inert; the introduction of air or other gases under pressure to said pot; the subsequent expansion of this air or other gas through the opening of the outlet port thus permitting a small portion of the 40 mass of molten metal to flow under pressure through said port into a mold; the closing of said port, and the venting of the melting pot.

In the practice of the herein described art 45 or method, I employ an apparatus as shown in the accompanying drawings, embodying therein a furnace having an outer shell *a* provided with a refractory lining *b*. Mounted and suitably braced within said 50 shell is a bottom pour melting pot *c*, having a constricted lower portion, the walls of which converge toward the outlet port *d*. The top of the said melting pot is closed and sealed against heavy pressures by the fixed 55 top *e* and the removable top section *f*, held in place and sealed by the clamp bar *f'*, this removable top section being provided to facilitate the introduction of metal into the melting pot.

60 Extending about the constricted portion of the melting pot *c* is an ordinary force feed gas burner *g*, the jet openings of which are so directed as to cause the heating flame to impinge upon the melting pot adjacent to 65 and about the outlet port *d*, thus causing

the zone of highest temperature to be near and at the bottom of said pot.

Normally closing the port *d* is a reciprocating valve *h* the stem *h'* of which passes through a suitable stuffing box *h* carried by the top *e*. The upper projecting end of the stem has a spring rigging *i* acting thereon to normally close the valve. The stem *h'* is enlarged within the melting pot, as at *h*³, to secure stiffness and avoid weakening through contact with the molten metal. The melting pot is without obstruction save the valve stem. The valve proper *h* and port *d* are slightly tapered to insure a proper seating of the valve, and said valve is elongated to project through said port to avoid any possibility of the port being clogged, although the high temperature about said port would prevent chilling of the metal therein.

Discharging into the upper portion of the melting pot *c* is a pipe line *j* having a three way valve *k* in its length, which valve is used to control the pressure within said pot.

I provide an ordinary pressure gauge *j'* communicating with the melting pot, for indicating the pressure within the pot. The exterior of the bottom of the melting pot *c* about the port *d* is planed and finished as at *d'* to form a seat upon which the mold about its ingate is adapted to seat to form a tight joint to avoid the escape of the molten metal.

Below, and extending beneath the melting pot *d* are tracks *m m'* upon which the mold, indicated at *n* is adapted to slide to bring its ingate into the operative relation to the port *d*, or withdraw it from this position to permit the convenient ejection of the casting. These tracks are supported by adjustment screw rods *o p*, so that the height of these tracks may be regulated to accommodate the apparatus to molds of different dimensions.

Arranged directly below the outlet port *d* is a vertically movable platform *q* adapted to engage the die and force it toward the melting pot, to form a metal to metal joint between the die and the melting pot. This platform is supported by a screw threaded stem *q'* having adjustably mounted thereon the cam disk *q*² acted upon by the co-operating lifting cam *r* having an actuating handle *r'*. The tracks *m m'* and cam *r* are supported by the bed *s* of the machine. The screw rod *o* is adapted to be actuated by the wheel handle *o'*.

The tracks *m m'* are provided with suitable stops *m*² *m*³, for limiting the reciprocating movement of the bed *t*, by means of which the mold *n* is mounted on the said tracks.

To avoid possibility of escaping metal being thrown upon the operator, I provide the shield *u* slideable within the shell *a* so as to afford clearance for the mold in its movement along the tracks *m m'*. This shield is provided with an operating handle *u'* mov-

ing in a bayonet slot u^2 in the shell a , so as to permit the locking of the shield in the raised position.

To avoid the setting or "freezing" of the metal in the ingate of a mold, I preferably provide the mold with a removable ingate comprising a downwardly converging tapered head v adapted to fit within a correspondingly tapered opening n' in the die proper. This head is provided with a downing in a bayonet slot u^2 in the shell a , so as to give the proper draw from the sprue indicated at w . Formed on the head v and the top of the mold n are coöperating cam surfaces v^2-n^2 for raising the head v or drawing it from about the sprue w . To facilitate the turning of the head v , I provide it with a handle v^3 .

The upper and lower parts of the die are hinged together by means of slotted brackets x , and coöperating pins y , this construction being desirable as permitting that parallel movement of the die parts desirable in the ejection of the casting.

The operation of the herein described apparatus in the practice of my art or method is substantially as follows:—The die n being closed, the head v is inserted in the opening n' , and the die advanced upon the tracks $m-m'$ until said ingate v is directly below the outlet port d . The cam r is then turned by means of its handle r' to force the die into the necessary close contact with the seat d' through the platform q , screw q' and cam q^2 . If the desired close contact is not thus secured, the tracks may be raised by means of the rods $o-p$. The mold having been properly set, the shield u is lowered and the valve k actuated to admit the air or other gas under pressure into the upper part of the melting pot c . The lever l is then used to raise the valve k and open the outlet port d whereupon a charge of metal from the bottom of the melting pot will be instantaneously forced into the mold through said port, through the expansion of said air or other gas. The handle l is immediately released, thus permitting the spring rigging i to automatically actuate the valve k to close said port d . Substantially simultaneously with the closing of said port, the valve k is actuated to vent the melting pot and relieve the pressure therein. The casting being completed, the shield u is raised and locked in the raised position, the cam r returned to normal to lower the mold, and the mold drawn to the position shown in Fig. 1, to permit the ejection of the casting. Before opening the mold, the removable sprue former is turned by means of the handle v^3 thus causing the cams v^2-n^2 to raise the head v , drawing the tapered opening v' away from the sprue.

The operations above described may be rapidly repeated by an operator in the or-

der specified to permit the rapid production of a number of castings from the same mold.

It is not my intention to limit my invention to the precise details of construction shown in the accompanying drawings, it being apparent that such may be varied without departing from the spirit and scope of my invention.

Having described my invention, what I claim as new and desire to have protected by Letters Patent, is:—

1. An art or method of casting fluid metals embodying therein the subjection of a confined mass of molten metal contained in a bottom pour melting pot to fluid under pressure, thereafter permitting a small portion of the molten metal to flow downwardly through the outlet port of said melting pot and into a mold under such pressure and thereafter simultaneously closing said port and forcing the metal therein outwardly of said melting pot.

2. An art or method of casting fluid metals embodying therein the subjection of a confined mass of molten metal contained in a bottom pour melting pot to fluid under pressure, permitting said air or gas to expand by permitting the molten metal to flow through the outlet port of said melting pot into a mold and thereafter simultaneously closing said port and forcing the metal therein outwardly of said melting pot.

3. An art or method of casting fluid metals embodying therein the subjection of a confined mass of molten metal contained in a bottom pour melting pot to fluid under pressure, thereafter permitting a small portion of the molten metal to flow downwardly through the outlet port of said melting pot and into a mold under such pressure, simultaneously closing said port and forcing the metal therein outwardly of said melting pot,

4. An art or method of casting fluid metals, embodying therein the fusion of a mass of metal in a bottom pour melting pot by a flame directed adjacent the outlet port of said pot, normally confining said metal within said pot, subjecting the entire mass of molten metal while so confined to fluid under pressure, thereafter permitting a small portion of the molten metal to flow downwardly through the outlet port of said melting pot and into a mold under such pressure and thereafter simultaneously closing said port and forcing the metal therein outwardly of said melting pot.

5. An art or method of casting fluid metals, embodying therein the fusion of a mass of metal in a bottom pour melting pot by a flame directed adjacent the outlet port of said pot, normally confining said metal within said pot, subjecting the entire mass of molten metal while so confined to fluid under

pressure, thereafter permitting a small portion of the molten metal to flow downwardly through the outlet port of said melting pot and into a mold under such pressure, simultaneously closing said port and forcing the metal therein outwardly of said melting pot, and relieving the pressure within said melting pot.

6. An apparatus for casting fluid metals embodying therein a melting pot having an outlet port in the bottom thereof, said outlet port having a beveled valve seat about same and within said pot, a furnace adapted to fuse metal in said pot, a valve having a tapered portion adapted to conform to said valve seat, and an elongated extension below said tapered portion and projecting through said port, said valve normally closing said outlet port, means for actuating said valve, 70 a pipe line adapted to deliver air or other gases under pressure to said melting pot, a valve mechanism for controlling the flow of air or other gases to and from said pot, and means whereby a mold may be supported with its ingate in communication with said outlet port.

7. An apparatus for casting fluid metals embodying therein a melting pot having side walls converging toward the bottom thereof and an outlet port in the bottom thereof, said port having a beveled valve seat about same within said melting pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, and means whereby a mold may be supported with its ingate in communication with said outlet port.

8. An apparatus for casting fluid metals embodying therein a melting pot, having an outlet port in the bottom thereof, said port having a beveled valve seat about same within said melting pot, a burner, the outlet openings of which are directed toward and about the bottom of said melting pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, and means whereby a mold may be supported with its ingate in communication with said outlet port.

9. An apparatus for casting fluid metals

embodying therein a melting pot having an outlet port in the bottom thereof, said outlet port having a beveled valve seat about same and within said pot, a furnace adapted to fuse metal in said pot, a valve having a tapered portion adapted to conform to said valve seat, and an elongated extension below said tapered portion and projecting through said port, said valve normally closing said outlet port, means for actuating said valve, 75 a pipe line adapted to deliver air or other gases under pressure to said melting pot, a valve mechanism for controlling the flow of air or other gases to and from said pot, means whereby a mold may be supported with its ingate in communication with said outlet port, a support for a mold extending below said outlet port of said melting pot, and means for adjusting said support toward and from said melting pot whereby said support may be adjusted to molds of different sizes.

10. An apparatus for casting fluid metals; embodying therein a melting pot having an outlet port in the bottom thereof, said outlet port having a beveled valve seat about same and within said pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said 100 melting pot, a valve mechanism for controlling the flow of air or other gases to and from said pot, and means whereby a mold may be supported with its ingate in communication with said outlet port.

11. An apparatus for casting fluid metals embodying therein a melting pot having an outlet port in the bottom thereof, said outlet port having a beveled valve seat about same and within said pot, a furnace adapted to fuse metal in said pot, a valve having a tapered portion adapted to conform to said valve seat, and an elongated extension below said tapered portion and projecting through said port, said valve normally closing said 110 outlet port, means for actuating said valve, a pipe line adapted to deliver air or other gases under pressure to said melting pot, a valve mechanism for controlling the flow of air or other gases to and from said pot, means whereby a mold may be supported with its ingate in communication with said outlet port, and means adapted to engage a mold and force it into intimate contact with the melting pot adjacent its outlet port.

12. An apparatus for casting fluid metals embodying therein a melting pot having an outlet port in the bottom thereof, said outlet port having a beveled valve seat about same and within said pot, a furnace adapted to 130

6
fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, means whereby a mold may be supported with its ingate in communication with said outlet port, tracks extending below said melting pot and adapted to support a mold, and adjustment rods adjacent the ends of said tracks whereby said tracks may be raised or lowered to accommodate said support to molds of different sizes.

13. An apparatus for casting fluid metals embodying therein a melting pot having an outlet port in the bottom thereof, said port having a beveled valve seat about same within said melting pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, means whereby a mold may be supported with its ingate in communication with said outlet port, means for adjusting said support toward and from said melting pot whereby said support may be adjusted to molds of different sizes, a vertically slidable screw rod, a platform carried thereby adapted to engage the mold, a cam plate adjustably mounted upon said screw rod, a cam cooperating with said cam plate supported by the frame of the machine, and an operating handle for said last named cam whereby said platform may be raised or lowered to force the mold into intimate contact with the melting pot.

14. An apparatus for casting fluid metals embodying therein a melting pot having an outlet port in the bottom thereof, said outlet port having a beveled valve seat about same and within said pot, a furnace adapted to fuse metal in said pot, a valve having a tapered portion adapted to conform to and seat upon said beveled valve seat and an elongated portion below said tapered portion and extending through said port, a spring rigging acting on said valve to cause it to normally close said outlet port, means for actuating said valve, a pipe line adapted to deliver air or other gases under pressure to said melting pot, a valve mechanism for controlling the flow of air or other gases to and from said pot, and means whereby a

mold may be supported with its ingate in communication with said outlet port.

15. An apparatus for casting fluid metals embodying therein a melting pot having an outlet port in the bottom thereof, said port having a beveled valve seat about same within said melting pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, tracks extending below said melting pot, and a mold carrier slidably mounted thereon whereby a mold may be brought into the operative relation to said melting pot or withdrawn therefrom to permit the ejection of a casting.

16. An apparatus for casting fluid metals embodying therein a melting pot having an outlet port in the bottom thereof, said port having a beveled valve seat about same within said melting pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, tracks extending below said melting pot, a mold carrier slidably mounted thereon whereby a mold may be brought into the operative relation to said melting pot or withdrawn therefrom to permit the ejection of a casting, and stops carried by said tracks for limiting the direct and return movement of said mold carrier to accurately position it with relation to said outlet port and to check its movement away from said melting pot.

17. An apparatus for casting fluid metals embodying therein a melting pot having an outlet port in the bottom thereof, said port having a beveled valve seat about same within said melting pot, a furnace adapted to fuse metal in said pot, a valve having a tapered portion adapted to conform to said valve seat, and an elongated extension below said tapered portion and projecting through said port, said valve normally closing said outlet port, means for actuating said valve, a pipe line adapted to deliver air or other gases under pressure to said melting pot, a valve mechanism for controlling the flow of air or other gases to and from said pot, means whereby a mold may be supported

with its ingate in communication with said outlet port, and a movable shield adapted to be interposed between said melting pot and the operator when said mold is in the operative relation to said melting pot, and to be withdrawn to permit the passage of said mold from beneath said melting pot.

18. An apparatus for casting fluid metals embodying therein a melting pot having an outlet port in the bottom thereof, a furnace adapted to fuse metal in said pot, a valve normally closing said outlet port, means for actuating said valve, a pipe line adapted to deliver air or other gases under pressure to said melting pot, a valve mechanism for controlling the flow of air or other gases to and from said pot, means whereby a mold may be supported with its ingate in communication with said outlet port, a shell inclosing said melting pot and said furnace, a shield slidable vertically within said shell, said shell having a bayonet slot therein, and an operating handle carried by said shield and moving in said slot whereby said shield may be raised to permit the passage of a mold under said shell and may be interposed between the melting pot and the operator while the mold is in the operative relation to the melting pot.

19. In an apparatus for casting fluid metals, a sprue former separable from the

mold, and adapted to be interposed between the mold and the melting pot, said sprue former comprising a frusto-conical head having an inversely directed frusto-conical opening therein, whereby said sprue former may be fitted accurately to a mold and will draw readily away from the sprue formed thereby.

20. In an apparatus for casting fluid metals, a sprue former separable from the mold, and adapted to be interposed between the mold and the melting pot, said sprue former comprising a frusto-conical head having an inversely directed frusto-conical draw readily away from the sprue formed may be fitted accurately to a mold and will draw readily away from the sprue formed thereby, said sprue former and said mold being provided with coöperating cam surfaces for facilitating the raising of said head, and said head being provided with an operating lever handle.

In witness whereof, I have hereunto affixed my signature, in the presence of two subscribing witnesses, this 29th day of July, 1913.

OLIVER G. SANDAGE.
